(57) **CLAIM**

The ornamental design for a carton with removable lid, as shown and described.

DESCRIPTION

FIG. 1 is a perspective view of a carton with removable lid showing the new design;

FIG. 2 is a front elevation view thereof, the rear being a mirror image;

FIG. 3 is left side elevation view thereof, the right side being a mirror image;

FIG. 4 is a top plan view thereof;

FIG. 5 is bottom plan view thereof;

FIG. 6 is another perspective view of the carton with removable lid of FIG. 1 shown without the removable lid;

FIG. 7 is a front elevation view thereof, the rear being a mirror image;

FIG. 8 is left side elevation view thereof, the right side being a mirror image;

FIG. 9 is a top plan view thereof;

FIG. 10 is bottom plan view thereof;

FIG. 11 is a top plan view of the carton of FIG. 6 in a blank configuration;

FIG. 12 is a top plan view of the carton of FIG. 11 shown in an alternate blank configuration;

FIG. 13 is a top plan view of the carton of FIG. 11 shown in another alternate blank configuration; and,

FIG. 14 is a top plan view of the removable lid only of FIG. 1, the bottom being a mirror image.

In the Figures, the broken lines illustrate perforations and form part of the claimed design.

1 Claim, 14 Drawing Sheets
